UNITED STATES PATENT OFFICE

WAYNE E. VESEY, OF PLYMOUTH, WISCONSIN, ASSIGNOR TO K-P-C COMPANY, OF CHICAGO, ILLINOIS, A CORPORATION OF ILLINOIS

MACHINE FOR LINING BOXES

Application filed July 5, 1927. Serial No. 203,285.

This invention relates to machines for lining boxes such as, for example, wooden boxes used for packaging food stuff.

One object of the invention is to provide a machine such as above referred to, which is operable to place a sheet of lining material in a box and to cause the lining sheet to lie smoothly and closely adjacent the inner walls of the box.

Another object is to provide such a machine which will have means for automatically feeding a plurality of boxes successively to the means for inserting the lining sheets, and still another object is to provide means for feeding lining sheets one at a time to said inserting means, and to feed such sheets one at a time from a pile of lining sheets disposed to one side of the box to be lined, to a position over the box preparatory to insertion of the sheet into the box.

Still other objects are to provide means for inserting a lining sheet into a box and for simultaneously folding portions of the sheet, which are adapted to serve as flaps to be folded over the top of the material subsequently packed in the box, downwardly along the outer walls of the box; to provide such a machine which will be relatively simple in construction, durable and unlikely to become out of working order, and in general, to provide an improved machine of the class described.

Other objects and advantages of the invention will be understood by reference to the following specification and accompanying drawings in which I have illustrated a machine embodying a selected form of the invention, and in which:

Fig. 1 is a plan.

Figs. 2, 3 and 4 are sections on the lines 2—2, 3—3 and 4—4 respectively of Fig. 1.

Fig. 5 is a detail illustration of certain valve mechanism.

Fig. 6 is a detail illustration of a yielding connecting rod.

Fig. 7 is a side elevation of the means for feeding the lining sheets from the pile of lining sheets to the box.

Fig. 8 is a view similar to Fig. 7, but

showing the mechanism in a changed position.

Fig. 9 is a detail section of the means for picking up and carrying the lining sheets from the pile to the box, and

Fig. 10 is a fragmentary perspective illustrating the type of box which the present embodiment of my invention is adapted to line and also illustrating a liner in place in the box.

Referring now to the drawings, and particularly Fig. 1, I have indicated a pair of chains 11 and 12 for feeding a plurality of boxes successively to a predetermined position indicated at "A", where a plunger 13 is adapted to force a sheet of lining material into the box. A pile of lining sheets is indicated at 14 supported by a suitable table or other support 15, and a pair of carrying devices 16 and 17 are provided for feeding the lining sheets from the pile 14 to a position over the box position "A" preparatory to insertion of the sheet into the box by the plunger 13. When the sheet has been inserted into the box, the box is fed beyond the position "A" to the discharge end D of the machine, where the box is discharged to any suitable conveyor mechanism, or otherwise disposed of.

The conveyors 11 and 12 comprise chain members which engage sprockets 19 and 20 which are fixed to a shaft 21, which shaft is rotatably mounted in suitable brackets 22 and 23 which are secured to adjacent portions of the main frame 24. The chains also engage suitable sprockets, one of which is indicated at 25, which are rotatably mounted on the main frame and serve to spread the upper and lower reaches of the chain so as to facilitate mounting of other mechanism between the said upper and lower reaches. Each of the chains also engage suitable rotatably mounted sprockets at the feed end "F" of the machine which arrangement will be readily understood by those skilled in the art and therefore, is not illustrated in the drawings.

The chains forming the conveyor are each provided with suitably spaced stops or lugs 26 which are adapted to engage a portion of

the boxes "B" as clearly shown in Fig. 2, and thereby to cause the boxes to travel with the chains whereby the latter are effective to feed the boxes to the position "A" above referred to, and subsequently to carry the boxes away from such position to the discharge end of the machine.

The various working parts of the machine may be driven by any suitable means and in the present instance I prefer to provide an electric motor 27 to supply the driving power. Since the usual types of electric motors run at a relatively high rate of speed, I prefer to provide a speed reduction mechanism such an indicated at 28 to which the motor is connected at 29, and which delivers power by means of a relatively slowly rotating shaft 30. A gear 31 is secured to the shaft 30 and this gear meshes with another gear 32 which is rotatably mounted on a shaft 33, the latter being rotatably mounted in suitable bearings which are secured to the main frame 24. Suitable clutch mechanism 34 is provided for clutching the gear 32 to the shaft 33 so that the latter will be rotated thereby and a hand lever 35 is provided for controlling the clutch, the said hand lever being operatively connected to the clutch by suitable means such as a link 36 and lever 37. A sprocket 38 is secured to the shaft 33 so as to be rotated therewith and a chain 39 engages the said sprocket 38 and also sprockets 40 and 41 on the shafts 42 and 43 respectively. The sprockets 40 and 41 are secured to the respective shafts so that the latter are rotated when the shaft 33 is rotated and the shafts 42 and 43 are journaled in suitable bearings on the main frame.

A disk 44 is secured to the outer end of the shaft 43 as best shown in Figs. 1 and 4, and the disk 44 is provided with a crank pin 45 on which is pivotally mounted one end of a connecting rod 46, the other end of which is pivotally connected at 47 to one end of a rock arm 48, which arm is pivotally mounted on the shaft 21. A pawl 49 is pivotally connected at 50 to the other end of the rock arm 48 and the pawl is adapted to engage a ratchet 51 which is secured to the shaft 21. It will be understood that rotation of the disk 44 will be effective, through the connecting rod 46, to rock the rock arm 48 on the shaft 21 and that the pawl 49 carried by the rock arm will be effective to intermittently rotate the shaft 21 and thereby to impart intermittent or step by step movement to the conveyor chains 11 and 12. It will thus be seen that I have provided mechanism for feeding a plurality of boxes to the position "A" which means is operative to successively support the boxes in such position for an interval of time during which time other mechanism, which will presently be described, is actu-

ed to insert a sheet of lining material into the box.

As best shown in Figs. 1 and 3, I provide a table or support 15 for supporting a pile of lining sheets 14 and the support 15 is preferably mounted so as to be adjustable in a vertical direction by any suitable means such as arms 52 and 53, which are secured to the main frame 24 and provided with apertures 54 and 55 respectively, at their outer ends for receiving a rod 56 which is secured to the support 15. Set screws 57 and 58 may be provided for locking the rod 56 in any desired position of vertical adjustment in the apertures 54 and 55. Brackets 59 and 60 may be provided on the support 15 for positioning the pile of lining sheets on the support and the brackets 59 and 60 are preferably adjustable by means of a slot and bolt connection as clearly shown in Fig. 1.

The carrying devices 16 and 17 above referred to, are provided for feeding the lining sheets one at a time from the pile 14 to a position over a box in the position "A", shelves 61 and 62 being provided for receiving and supporting the lining sheet in this position. The carrying members 16 and 17 are of similar construction, and hence, only one, the member 17, will be described.

The carrying member 17 comprises an arm 63 which is secured to a rock shaft 64, the latter being rocked by means of a rock arm 65, connecting rod 66 and crank pin 67 secured to a rotating member 68. The member 68 is mounted on a shaft 69 which is journaled in suitable bearings, and this shaft is rotated by means of a beveled gear 70 secured to the shaft 69 and a beveled gear 71 on the rotating shaft 33, which meshes with the former. It will be understood that rotation of the member 68 and crank pin carried thereby will be effective to rock the shaft 64 and thereby to oscillate the rock arm 63.

A link 72 is pivotally connected at one end to the free end of the rock arm 63 and in the present embodiment is yieldingly connected at its other end to a rod 73, which rod is supported at its free end by means of a roller 74 mounted on a portion of the main frame. The yielding connection between the link 72 and rod 73 consists of a pin member 75 which is secured to the rod 73 as indicated at 76 by any suitable means, and which pin extends through a journal block 77, which is pivotally mounted on the link 72. A compression spring 78 is disposed around the pin 75 between the upper end of the journal block 77 and a collar 79 secured to the pin, and it will be seen that the spring 78 is effective to normally maintain the rod 73 in engagement with the lower end of the journal block 77.

Any desirable means may be provided on the inner end of the rod 73 for engaging and picking up the uppermost sheet of lining

material on the pile 14 and in the present instance I prefer to provide a suction cup 80, preferably of flexible material such as rubber, this cup being connected as best shown in Fig. 9, to a conduit member 81 which is pivotally mounted as indicated at 82 on the rod 73.

By an inspection of Figs. 7 and 8, it will be seen that movement of the rock arm 63 in one direction is effective to move the sheet engaging and carrying suction cup 80 from the position indicated in Fig. 7 to the position shown in Fig. 8 over the pile of lining sheets. The inner end of the rod 73 is guided in its movement by means of a wheel or roller 83 which is rotatably mounted on the pivot of the journal block 77 and which wheel travels over a guide member 84 having an inclined portion 85 at its inner end or end adjacent the pile of lining sheets. It will be seen that as the suction cup 80 approaches the pile of lining sheets, it is raised to a position above the uppermost sheet of the pile by means of the inclined portion 85 of the guide member 84. Such raised position is indicated at 86 in dotted lines.

Means is provided for depressing or lowering the suction cup into engagement with the uppermost sheet on the pile and this means in the present case consists of a spring pressed plunger 87 mounted on the link 72 so as to be in position to engage the top side of the rod 73 as clearly shown in Fig. 8. As the rock arm 63 and link 72 approach their extreme positions as shown in Fig. 8, the spring pressed plunger 87 engages the rod 73 and forces it downwardly. The yielding connection between the link 72 and the rod 73 permits separation thereof, as is also clearly shown in Fig. 8, thereby permitting the suction cup to be lowered into engagement with the uppermost sheet of the pile of lining sheets as shown in the said Fig. 8. It will be noted that by means of the yielding plunger member 87 which is provided for lowering the cup into engagement with the top of the pile of lining sheets, the device is operable to pick up the top sheet from the pile without maintaining the top of the pile at a definite fixed height. In other words, the sheet carrying device is operable to pick up and carry the top sheet from a pile of gradually diminishing height.

Movement of the rock arm 63 from the position shown in Fig. 8 back to the position shown in Fig. 7 will of course, cause the suction cup 80 to be returned to the position shown in Fig. 7, and means is provided for causing the uppermost sheet of the pile 14 to adhere to the suction cup 80 and be carried thereby from the pile to the position shown in the said Fig. 7 where a sheet of lining material is indicated at L. The means for causing the uppermost sheet to adhere to the suction cup 80 includes an exhaust pump 88

preferably of the centrifugal type, this pump being driven by means of a belt 89 engaging a pulley 90 on the pump shaft and a pulley 91 on the rotated shaft 42. The pump 88 is provided with intake and exhaust ports 92 and 93 respectively, of which the intake port 92 is connected by means of a pipe line 94 and flexible conduit 95 to the conduit member 81 and suction cup 80. The pipe line is preferably provided with a Y-fitting 96 so that both carrying members 16 and 17 can be served by the same pipe line and controlled by a single valve 97 which is interposed in the pipe line.

The rock arm 63 of the carrying mechanism 17 is connected by a transverse member 98 to the rock arm of the carrying member 16 and the transverse member 98 is provided with a cam plate 99 which is adapted to engage the valve control lever 100 to thereby turn the valve and shut off the exhaust from the suction cup when the arm reaches its limit of movement as shown in Figs. 3 and 7 and at which time the suction cup has carried a lining sheet to the position in which it is to be deposited. A suitable spring 101 may be provided for turning the valve to "on" position when the arm 63 is moved in the other direction to bring the suction cup over the pile of sheets to pick up and subsequently feed the next sheet. It will now be seen that I have provided mechanism for automatically controlling the exhausting effect of the pump 88 on the suction cup 80 so as to properly time the exhausting of air from the suction cup to cause a sheet of lining material to adhere to the cup until such time as the sheet is to be deposited in a new position.

In order to assist the suction cup to pick up only one sheet at a time from the pile 14, I provide a blower member 102 which is provided with a series of apertures as shown at 103 and connected to the exhaust port 93 of the pump by means of a pipe line 104. The blower 102 directs a current of air against the adjacent edge of the pile of lining sheets and tends to separate them so that the suction cup 80 will not pick up and carry more than one sheet at a time.

I prefer to provide means in the pipe line 94 for controlling the degree of vacuum produced by the exhaust pump 88 in the suction cup 80 and such means may comprise a spring controlled valve such as indicated at 105. This valve comprises a chamber 106 having a port 107 normally closed by a valve 108 which is retained in closed position by means of a spring 109 disposed around the stem 110 of the valve and between a lug 111 and a nut 112 which screw threadedly engages the outer end of the stem 110. It will be seen that by adjusting the nut 112, the compression of the spring 109 will be varied and the pressure with

which the valve 108 is held in closed position is accordingly varied. It will be readily understood that when the degree of vacuum becomes sufficient to permit outside atmospheric pressure to unseat the valve 108 against the pressure of the spring 109, the port 107 will be opened and the atmospheric air will be permitted to enter the pipe line 94, and I am thus able to adjust the degree

10 of vacuum produced by the pump in the suction cup 80 to adapt the mechanism for feeding lining sheets of various kinds and weights. In the present instance, I contemplate feeding sheets of tin-foil or the like 15 which has been found to be very effective for preserving food stuff when wrapped thereabout, but it is obvious of course, that lining sheets of other material may be fed with equal facility.

20 After the carrying members 16 and 17 feed the sheet of lining material onto the shelf members 61 and 62, it is desired to insert the sheet into one of the boxes B. For this purpose I provide a plunger 13 which is 25 slidably mounted in a pair of track members 114 and 115. The track members 114 and 115 are fixedly mounted on the main frame 24 and the plunger is reciprocated upwardly and downwardly by means of a 30 connecting rod 116 which is pivotally connected at one end to a stud 117 projecting rearwardly from the plunger member 13 and pivotally connected at its other end to the crank pin 45 on the rotating disk 44.

35 It will be seen that as the disk 44 rotates, the connecting rod 116 will be effective to impart reciprocation movement to the plunger 13, which plunger is adapted to engage the sheet of lining material previously deposited on the shelves 61 and 62 and to force the same into a box which is temporarily held stationary in a position directly beneath the plunger.

The plunger is also preferably provided 45 with folding plates 118 and 119 for folding a marginal portion of the lining sheet downwardly on the outside of the box as indicated at 120. The width of the plunger 13 is preferably such as to cause the lining 50 sheet to lie closely adjacent the inner walls of the box so that when food stuff is packed thereinto, there will be a relatively small amount of movement of the lining sheet caused by the insertion of such food stuff, 55 after which the marginal portions or flaps 120 may be folded over the top of the contents of the box to cover the said top.

The disk 44 is continuously rotated and the plunger 13 is accordingly continuously reciprocated. The box feeding mechanism is synchronized in its movement with the movement of the plunger so that the box will be held stationary in proper position under the plunger so that the plunger will enter the 60 box on each of its down strokes. As shown

in Fig. 2, the plunger is in its up position and the boxes are being moved forward by the conveyor so that by the time the plunger 13 is again lowered to a position in which its bottom is almost even with the tops of the boxes, the boxes will be stopped in their movement with an unlined box in proper position for the plunger to continue its movement thereinto.

70 In order to prevent any possible injury to the mechanism, I prefer to make the connecting rod 116 of a yielding type and for this purpose I provide the structure shown in Fig. 6. The connecting rod there shown includes an upper member 121 which is 75 pivotally connected to the stud 117 of the plunger and provided with a relatively long sleeve member 122 which is adapted to slidably receive a rod portion 123 of the lower connecting rod member 124 which is pivotally mounted on the crank pin 45. The two connecting rod members 121 and 124 are maintained in normally operative position by means of a pair of coil springs 125 and 126 which are adapted to yield and 80 permit relative movement of the two connecting rod members in case an obstruction should prevent full movement of the plunger in the downward direction.

85 In the present embodiment of my machine 95 I have shown means for lining two sides and the bottom of a box and it is contemplated that separate sheets of lining material will be placed over the ends of the box either manually or by other automatic means 100 to thereby form a complete lining for the box. The present machine is, however, effective to rapidly and accurately position the lining sheets in the box as above described, and the machine is relatively simple 105 in its construction and operation, and will not readily become inoperative.

The described details being merely illustrative of a single embodiment of my invention, it will be understood that the scope 110 of the same should be determined by reference to the following claims which should be construed as broadly as possible consistent with the state of the art.

115 I claim as my invention:

1. In a machine of the class described, means for feeding lining sheets or the like one at a time from a pile of sheets to a predetermined position to one side of said pile, said means including means for engaging the uppermost sheet on said pile, yielding means for effecting such engagement, whereby said engaging means is adapted to successively engage the top sheet at a gradually lowering height incidental to the progressive removal of sheets from the pile, means for causing said uppermost sheet to adhere to said engaging means, means for initially raising said engaging means and a portion of the sheet adhering thereto and 120

- subsequently moving said engaging means and the sheet carried thereby to one side of the pile, and means for causing said sheet to be released from said engaging means thereby to deposit the sheet in said predetermined position.
2. In a machine of the class described, means for feeding the top sheet of a pile of sheets from said pile to a position alongside the pile, said means including a longitudinally movable rod, a suction cup connected to one end of said rod so as to be movable therewith to a position over the pile of sheets, a pivotally mounted arm, means for oscillating said arm on its pivot, a link pivotally connected at one end to the free end of said arm and connected at its opposite end to said rod adjacent said suction cup, said arm and link being effective to reciprocate said rod as an incident to the oscillation of the arm, whereby the cup is moved to said position above said top sheet, means for lowering said suction cup into engagement with said top sheet, means for causing said top sheet to adhere to said suction cup whereby the latter is adapted to carry the sheet from said pile to said position alongside the pile as an incident to the reciprocation of said rod in the reverse direction.
3. In a machine of the class described, means for feeding the uppermost sheet of a pile of sheets from said pile to a position alongside said pile and comprising a movably mounted member for engaging said sheet and having means for causing the sheet to adhere thereto, means for moving said engaging member to a position over said uppermost sheet, means for yieldingly lowering said member into engagement with the sheet, whereby said engaging means is adapted to successively engage the top sheet at a gradually lowering height incidental to the progressive removal of sheets from the pile, said means for moving said engaging member being also operative to move the member in the reverse direction, thereby to cause the member to lift a portion of the sheet away from said pile and subsequently to carry the sheet to said position alongside the pile, and means for causing the sheet to be released from said engaging means, thereby to deposit the sheet in said position.
4. In a machine of the class described, means for feeding the top sheet of a pile of sheets from said pile to a position alongside the pile, said means including a longitudinally movable rod, means for guiding said rod as it is moved, an engaging member connected to one end of said rod and adapted to be moved therewith to a position over the pile of sheets, a pivotally mounted arm, means for oscillating said arm on its pivot, a link pivotally connected at one end to the free end of said arm and connected at its opposite end to said rod adjacent said suction cup, said arm and link being effective to reciprocate said rod as an incident to the oscillation of the arm, whereby the cup is moved to said position above said top sheet, means carried by said link for engaging said rod to lower said member into engagement with said top sheet, means for causing said top sheet to adhere to said suction cup whereby the latter is adapted to carry the sheet from said pile to said position alongside the pile as an incident to the reciprocation of said rod in the reverse direction.
5. In a machine of the class described, means for feeding the top sheet of a pile of sheets from said pile to a position alongside the pile, said means including a longitudinally movable rod, means for guiding said rod as it is moved, an engaging member connected to one end of said rod and adapted to be moved therewith to a position over the pile of sheets, a pivotally mounted arm, means for oscillating said arm on its pivot, a link pivotally connected at one end to the free end of said arm and connected at its opposite end to said rod adjacent said suction cup, said arm and link being effective to reciprocate said rod as an incident to the oscillation of the arm, whereby the cup is moved to said position above said top sheet, means for lowering said member into engagement with said top sheet, means for causing said top sheet to adhere to said member whereby the latter is adapted to carry the sheet from said pile to said position alongside the pile as an incident to the reciprocation of said rod in the reverse direction.
6. In a machine of the class described, means for feeding the top sheet of a pile of sheets from said pile to a position alongside the pile, said means including a longitudinally movable rod, a suction cup connected to one end of said rod so as to be movable therewith to a position over the pile of sheets, a pivotally mounted arm, means for oscillating said arm on its pivot, a link pivotally connected at one end to the free end of said arm and connected at its opposite end to said rod adjacent said suction cup, said arm and link being effective to reciprocate said rod as an incident to the oscillation of the arm, whereby the cup is moved to said position above said top sheet, means carried by said link for engaging said rod to lower said suction cup into engagement with said top sheet, means for causing said top sheet to adhere to said suction cup whereby the latter is adapted to carry the sheet from said pile to said position alongside the pile as an incident to the reciprocation of said rod in the reverse direction.
7. In a machine of the class described, means for feeding the top sheet of a pile of

- sheets from said pile to a position alongside the pile, said means including a longitudinally movable rod, means for guiding said rod as it is moved, a suction cup connected to one end of said rod and adapted to be moved therewith to a position over the pile of sheets, a pivotally mounted arm, means for oscillating said arm on its pivot, a link pivotally connected at one end to the free end of said arm and having a yielding connection at its opposite end to said rod adjacent said suction cup, said arm and link being effective to reciprocate said rod as an incident to the oscillation of the arm, 5 whereby the cup is moved to a position over said top sheet, means acting against the tension of said yielding connection for lowering said suction cup into engagement with said top sheet, and means for causing the 10 top sheet to adhere to said suction cup, whereby the latter is adapted to carry the sheet from said pile to said position alongside the pile as an incident to reciprocation of said rod in the reverse direction.
- 15 8. In a machine of the class described, means for feeding the top sheet of a pile of sheets from said pile to a position alongside said pile, said means including a longitudinally movable rod, a suction cup connected to one end of said rod so as to be movable therewith to a position over the pile of sheets, a pivotally mounted arm, means for oscillating said arm on its pivot, a link pivotally connected at one end to the free 20 end of said arm and having a yielding connection at its opposite end to said rod adjacent said suction cup, said arm and link being effective to reciprocate said arm as an incident to oscillation of the arm, means for raising the cup and adjacent end of the 25 rod as the rod is moved toward the pile, whereby the cup is moved to said position over the pile, means acting against the tension of said yielding connection for lowering said suction cup into engagement with said top sheet, said yielding means being effective to successively lower said cup into engagement with the top sheet of a pile of sheets, the height of which is successively lowered sheet by sheet. 30
- 35 10. In a machine of the class described, means for feeding the top sheet of a pile of sheets from said pile to a position alongside the pile, said means including a longitudinally movable rod, a suction cup connected to one end of said rod so as to be movable therewith to a position over the pile of sheets, a pivotally mounted arm, means for oscillating said arm on its pivot, a link pivotally connected at one end to the free 40 end of said arm and having a yielding connection at its opposite end to said rod adjacent said suction cup, said arm and link being effective to reciprocate said rod as an incident to oscillation of the arm, means for raising the cup and adjacent end of the 45 rod as the rod is moved toward the pile, whereby the cup is moved to said position over the pile, means acting against the tension of said yielding connection for lowering said suction cup into engagement with said top sheet, said yielding means being effective to successively lower said cup into engagement with the top sheet of a pile of sheets, the height of which is successively lowered sheet by sheet. 50
- 55 11. In combination in a machine for successively feeding the top sheet of a pile of sheets to a position alongside the pile, a sheet pick-up member, a rock arm, means for oscillating said rock arm, means connecting the free end of said arm with said pick-up member for effecting reciprocation of the pick-up member as an incident to the oscillation of said arm, said connecting means being such as to permit movement of the pick-up member transversely of the direction of its reciprocating movement and means operative as an incident to the movement of said rock arm for effecting such transverse movement of said pick-up member into engagement with the top sheet of the pile of sheets. 60
- 65 12. In a machine for feeding sheets from the top of a pile of sheets to a position alongside the pile, the combination of a sheet pick-up member, a rock arm, means for oscillating said arm, means connecting the free end of said arm with said pick-up member for effecting reciprocation of the pick-up member as an incident to the oscillation of

said arm, said means permitting movement of said pick-up member transversely of the direction of its reciprocating movement, and yielding means operative as an incident to the movement of said rock arm for effecting such transverse movement of said pick-up means into engagement with the top sheet of the pile of sheets.
